United States Patent Office.

WILLIAM E. PRALL, OF WASHINGTON, DISTRICT OF COLUMBIA.

Letters Patent No. 77,090, dated April 21, 1868.

IMPROVEMENT IN HOT-WATER ELEVATORS.

The Schedule referred to in these Letters Patent and making part of the same.

TO ALL WHOM IT MAY CONCERN:

Be it known that I, WILLIAM E. PRALL, of the city of Washington, District of Columbia, have invented a new and improved Mode of Elevating Hot Water in Dwellings where the conveniences of public water-works cannot be obtained; and I do hereby declare that the following is a full and exact description thereof, reference being had to the accompanying drawings, and to the letters of reference marked thereon.

The nature of my invention consists in placing, within a furnace, a heating-chamber, A, which is connected to a well or cistern by means of a pipe, B. Said pipe is provided with a valve, C, and cold-water chamber D, situated above and adjacent to the heating-chamber, or the valve may be placed at the lower end of the pipe under the water.

There is also a discharge-pipe, E, connecting with the heating-chamber, situated below the supply-pipe, and extending to the boiler and to the tank placed at the top of the house. This pipe is also provided with a valve, F, placed near the heating-chamber.

There may be more than one valve in each pipe, or their positions may be changed to produce the most uniform flow of water. A pipe, G, attached to the heating-chamber, near the point where the supply-pipe enters, and connecting with the cold-water chamber at the top, is also provided, for the purpose of equalizing the pressure on each side of the cold-water chamber from the steam in the heating-chamber, so that the heating-chamber may be immediately refilled by the specific gravity of the water in the cold-water chamber.

On filling the heater and pipes with water and applying the heat, steam is generated in the heater, the force of which closes the valve in the supply-pipe, and opens the valve in the discharge-pipe, forcing the water from the heater through the discharge-pipe, as low as the point where the supply-pipe enters the heater, (which is above the discharge-pipe,) when the cold water from the cold-water chamber is ejected, which condenses the steam and creates a vacuum in the heater. This closes the valve in the discharge-pipe and opens the valve in the supply-pipe, and the heating-chamber is again refilled, and thus the water is drawn from the cistern by suction to the heater, and forced by the steam to the upper part of the house.

The water is conveyed from the tank to any part of the house, and the hot water is forced through pipes connecting with the boiler by the force of the column of water in the pipe extending to the tank from the boiler. A waste-pipe is attached to the tank to convey the water back to the cistern should it become filled. Cocks for draining the pipes are provided.

Claim.

In connection with a stove or like heater, and for domestic purposes, an automatic water-elevator, constructed and operating substantially and for the purpose set forth.

WM. E. PRALL.
